UNITED STATES PATENT OFFICE

2,165,613

APPARATUS FOR GRADING AND MARKING

Kenneth E. Conn, Bloomington, Ind.

Application September 18, 1937, Serial No. 164,603

5 Claims. (Cl. 35—48)

My invention relates to apparatus for grading and marking test papers, such as examination papers for grading students, or, competitors for various positions in industries or the like.

5 The invention is directed primarily toward providing apparatus for quickly and accurately ascertaining the number of correct answers given in a test without separately checking each answer, as is the usual practice, thereby saving 10 much time and labor.

Another object is the provision of efficient apparatus for automatically adding and registering the number of correct answers given in a test and automatically marking on the test paper the 15 correct answers.

Other and subordinate objects are also comprehended by my invention as will appear when the following description and the claims are read with reference to the drawings accompanying and 20 forming part of this specification.

In said drawings:

Figure 1 is a view in top plan of a paper holder and a combined registering and marking instrument forming a part of a preferred embodiment 25 of my invention,

Figure 2 is a view partly in side elevation and partly in section of the combined registering and marking instrument drawn to an enlarged scale,

Figure 3 is a fragmentary view of a test sheet 30 forming part of the invention,

Figure 4 is a similar view of a key sheet,

Figure 5 is a view in top plan illustrating the use of the holder and the test and key sheets,

Figure 6 is a view in top plan of a modified 35 form of holder,

Figure 7 is a view in longitudinal section taken on the line 7—7 of Figure 6,

Figure 8 is a fragmentary view of a color sheet 40 forming a part of a modified form of the invention,

Figure 9 is a similar view illustrating the use of the color sheet, and

Figures 10 and 11 are views in top plan and side elevation, respectively, of a sheet perforating 45 punch forming an adjunctive part of the apparatus.

Referring to the drawings by numerals, the basic elements of my invention in the preferred embodiment thereof are a sheet holder 1, such as 50 shown in Figure 1, a combined registering and marking instrument 2, a test sheet 3, shown in Figure 3, and a key sheet 4, shown in Figure 4. These basic elements will now be described in the order named.

55 The holder 1 comprises a flat rectangular base

plate 5, of any material functioning as a conductor of electricity, and having suitably secured thereto, along three side edges thereof, strips 7 of insulating material, preferably wood, forming together with the plate 5 a frame like structure 5 open at what may be termed the front side 8 thereof, or, of the holder 1. The plate 5 may be provided with an insulated backing, not shown. Preferably, although not necessarily, a plurality, three in this instance, of transversely flat bars 9, 10 also of insulating material, are inlaid in said plate 5 to extend from the front side 8 of said plate, said bars being spaced apart from the strips 7 to provide an exposed surface of the plate surrounding said bars for a purpose presently 15 seen. Bars 10, similar to bars 9, extend from the front side of the plate 5 to the strips 7 at the opposite, or, rear side thereof alongside the side bars 7. At the rear side of the holder, centrally thereof, is a triangular locator finger 11 extending inwardly from the rear bar 7 over the plate 5, and the purpose of which will presently be described. At the front side of the plate 5, also centrally thereof, is a concave finger accommodation aperture 12 presently referred to in detail. Opposite the locator finger 11 is a semi-circular ledge 13 formed by an extension of the plate 5 and for the attachment of wiring to the plate 5. The described frame structure may be varied as expediency may require for instance by eliminating the strips 9 and forming the plate 5 as a single 20 piece structure.

The combined registering and marking instrument 2 comprises a hollow handle 14 of insulating material, for instance hard rubber, provided 35 at one end with a cross bar 15 of conducting material, such as copper, and having suitably mounted thereon to extend therefrom a plurality of laterally spaced contact strips 16 of flexible conducting metal, the cross bar 15 and strips 16 40 forming a brush like unit for a use presently explained. Adjacent to the cross bar 15, and suitably secured to the handle 14 is a register or counter 17, of any suitable type, such as the well known Veedor counter, and including denominational value indicating wheels 18 visible through a sight opening 19 in said register and rotatable step by step, in a manner well understood in the art, by means of a toothed wheel 20, of the ratchet wheel type, fast on an operating shaft 21 45 extending from one side of said register.

The toothed wheel 20 is operative step by step by the following means. Mounted alongside the handle 14, with its axis in the plane of the wheel 20, and by a pair of rods 22 extending from said 50

55

handle 14 is a cylinder 23. Slidable axially in the cylinder 23 is a reciprocable wheel operating plunger 24 one end of which extends from one end of the cylinder 23 toward said wheel 20. Extending forwardly from said end of the plunger 24, and suitably secured thereto, is a wheel operating finger like dog 25 of resilient metal provided with a ratchet tooth 26 adapted in one direction of movement of the plunger 24, from normal position, to engage a tooth of the wheel 20 and impart a single step of rotation thereto, and in the other direction of movement of said plunger, to normal position, to wipe over the teeth of the wheel 20 idly. A coil spring 27 surrounding the plunger 24, in the cylinder 23, and interposed between one end of said cylinder and a pin 28 and the plunger, urges the latter toward normal position. The normal position of the plunger 24 is established by means of a flat head 29 on the end thereof opposite the finger end, engaging with the outer side of the adjacent end of the cylinder 23.

The plunger 24 is moved from normal position, against the tension of the spring 27, by means of an electromagnet 30 mounted alongside the handle 14 in axial alignment with the plunger 24, with its core 31 opposed to the head 29. The mounting for the magnet 30 comprises a pair of hollow arms 32 extending laterally from the handle 14 and communicating with both the interior of said handle and the outer casing 33 of the magnet 30. One side of the magnet 30 is wired by a lead 34 extending from the field, not shown, through one of the arms 32 to the cross bar 15. The other side of the magnet 30 is connected by a lead 35 extending from said field through the other arm 32, into the handle 14 and out of a nipple 36 on the rear end of said handle to one side of a source of energy represented at 37, for instance, the house current. The other side of the source of energy 37 is connected by a lead 38 to the beforementioned ledge 13 as by the binding post 39. The marking part of the instrument 2 comprises a pencil like marker 40 mounted in a cylindrical sleeve 41 for reciprocation in limited degree alongside the handle 14 with a pointed marking end thereof disposed alongside the series of contact strips 16. The sleeve 41 is mounted on the magnet 30 and on the cylinder 23 by a pair of arms 42 extending from said magnet and cylinder respectively. The arrangement of the marker 40 is such that in one limit of movement thereof the point of the marker will engage and drag on a sheet of paper when the contact strips 16 are drawn across such sheet, and in the other limit of movement thereof said marker is raised from said sheet. In the normal position thereof the marker 40 is adapted to engage the sheet. The plunger 24 is operatively connected to the marker 40 to move the latter from normal position and thereby disengage the same from the sheet of paper each time the plunger is moved from normal position, or, in other words, each time the register 17 is operated, all for a purpose presently to be made clear. The operating connection between the plunger 24 and the marker 40 comprises an arm 43 extending laterally from the plunger 24, a short sleeve 44 on said arm and through which said marker is extended, and a set screw 45 threaded into the sleeve 44 for adjustably clamping the marker in said sleeve.

The test sheet 3 is of the proper size to fit, at least the right hand half thereof, between the side strips 7 with the right hand edge thereof

engaged with the rear strip 7. Preferably the sheet 3 is tilted at the top, as at 46 and provided with blank spaces 47, 48, 49 and 49a for the name of the pupil, or competitor, date of the test, and school section and score, respectively. 5 Preferably the problems 50 are printed, or written, on the left hand side of the sheet 3 in column formation and numbered consecutively downwardly as at 51. However, other arrangements of the problems 50 may be resorted to if 10 desired. Following each problem 50 on the same side of the sheet 3 is a series of several selective answers 52, consecutively numbered, from left to right, one answer in each series being correct. At the right hand side of the sheet 3 opposite 15 each problem 50 is a line of consecutively arranged numbers 53 corresponding to the numbers of the answers in the problem and herein-after designated answer selecting numbers. Each line of answer selecting numbers 53 is followed by the number of the problem, as at 54, disposed at the right of said line. 20

The key sheet 4 is identical with the test sheet 3 so that the sheets being superposed, one on the other, with the edges thereof registering, the 25 answer selecting number 53 of each sheet will register line for line. Each sheet 3 and 4 is provided in its right hand edge with a V notch 55 for cooperation with the aforementioned locator finger 11 to facilitate superposing said sheets in 30 exact registration for a purpose presently appearing. The sheets 3 and 4 may be provided with perforations as at 3' and 4' respectively, to take over pegs 1' on the frame 1 to facilitate accurately aligning said sheets and positioning 35 the same on said frame.

The key sheet 4 is perforated through the answer selecting number in each line, as at 56, corresponding to that of the correct answer. The test sheet 3 is handed to the pupil, or, other 40 participant to be similarly perforated, as indicated by dotted lines in Figure 3, as at 57, according to the pupil's, or, other participant's selection of answers from those given on said sheet. A suitable form of punch 58, such as 45 shown in Figures 10, 11, is provided for this purpose.

Referring now to the use and operation of the described embodiment of my apparatus, the key sheet 4 is fitted right hand edge foremost into the holder 1, flat against the plate 5 and with the notch 55 thereof fitted over the locator finger 11, the right hand margin of the sheet disposed flat against the rear bar 7. The test sheet 3 is next fitted into the holder on top of the key sheet 55 4 in the same manner. In this position of said sheets 3 and 4 the answer selecting numbers 53 on said sheets are in registration line for line. At this point it may be explained that the bars 9 are disposed to underlie the sheets 3 and 4 60 intermediate the lines of answer selecting numbers 53, also the problems 50, so as to provide insulated areas over which the sheets 3 and 4 65 may be smoothed down without danger of the fingers receiving a shock from the plate 5. The bars 10 serve the same purpose at the top and bottom edges of said sheets. With these sheets 3 and 4 superposed as described, if the test sheet has been punched or perforated to punch out answer selecting numbers 53 corresponding to 70 those of the correct answers to the problem 50, the perforations, as at 57, in the test sheet 3 will register with those, 56, in the key sheet 4 thereby exposing the plate 5 through such registering perforations. If, on the other hand, the test 75

sheet 3 has been punched to punch out answer selecting numbers 53 corresponding to incorrect answers 52 of the problems 50, such perforations will not register with any in the key sheet 4 and said key sheet will cover the plate 5 under such incorrectly selected perforations. The sheets 3 and 4 being arranged as described, the combined registering and marking instrument 2 is manipulated over the test sheet 3 to brush the contact strips 16 down the column of answer selecting numbers 53, one line at a time. During such manipulation of the instrument 2, the contact fingers 16 will wipe over the plate 5 wherever said plate is exposed through registering perforations 56 and 57 and close a circuit to the electromagnet 30 thereby energizing said magnet. As will be obvious, the circuit is closed from the source of energy 31 through the lead 38, binding post 39, ledge 13, plate 5, contact strips 16, lead 34 and lead 35. Upon closing of the circuit the electro-magnet 30 will attract the plunger 24 thereby moving the same from normal position against the tension of the spring 27, the plunger and finger 25 effecting a single step of movement of the toothed wheel 20 each time said contact strips 16 wipe over an exposed area of the plate 5. As will be understood, each time the toothed wheel 20 is rotated one step the value one is accumulated in the register 17 so that the number of correct answers made by the student, or other participant, as indicated by perforations of correct answer selecting numbers 53, is registered in said register 17. As has been previously explained when the plunger 24 is moved from normal position, or in other words when register 17 is being operated, the marker 40 is raised from the sheet and therefore idle. Consequently whenever instrument 2 is manipulated down an answer column and passes over an answer correctly perforated it fails to contact, in the manner previously described, with the plate 5, said marker 40 being, as previously described, in engagement with the sheet leaves a mark opposite each incorrect answer in the column. This being the case a mark will be left, or made, alongside each answer selecting number 53 in the column which has been incorrectly selected by punching the same out of the sheet 3 and the incorrectness of the selection thereby indicated on the sheet. It will be understood that a succession of test sheets 3 are superposed on one key sheet 4 and graded and marked by the instrument 2 in the manner above described and the score recorded on each sheet 3 at 49a.

In the modified form of the invention illustrated in Figures 6 and 7, a holder 59 is provided for receiving and aligning the edges of test and key sheets of the type previously described so as to adjust said sheets into exact registration. The holder 59 comprises a base plate 60 of wood having the form of a rectangle. A pair of transversely extending slots 61 are provided in said plate 60 adjacent opposite ends thereof, respectively, opening at their bottoms into subjacent grooves 62 formed in the under side of said plate 60. One end of the base plate 60 is thicker than the remaining part of the plate to form a shoulder 63 at said end of said plate. A wooden bar 64 is mounted on said plate 60 for adjustment transversely thereof by means of headed screws 65 threaded upwardly through grooves 62, slots 61 and the ends of said bar, wing nuts 66 being threaded on the upper ends of said screws to clamp the bar 64 into adjusted position. At the shouldered end of the plate 60 said bar is pro-

vided with an extension 67 through which one of the screws 65 extends, said extension being provided to permit the bar 64 to fit flush against the shoulder 63. Intermediate the ends of the holder 59 is a transversely extending wooden bar 68 adjustable longitudinally of the holder. For this purpose the bar 64 is slotted longitudinally as at 69 and one edge of the base plate 60 has suitably secured thereto a metal bar 70 forming together with the said edge of the plate 60 a slot 71 opposite and parallel to the slot 69. Set screws 72, similar to screws 65, inserted through said slots 69 and 71 and through bar 68, with wing nuts 73 threaded onto their upper ends, provide for adjustment of the bar 68 longitudinally of the holder and clamping of the same in adjusted positions. An extension 74 on the appropriate end of the bar 68, and through which the screw 72 at that end of the bar extends, permits said end of the bar to fit flush against the adjacent side of the bar 64. A longitudinally extending slot 75 in the bar 68, through which one of the screws 72 extends, permits movement of the bar 68 transversely of the holder with the bar 64. A plate 76 similar to plate 5 is suitably secured to the upper face of the plate 60 with its edges spaced from the edges of the latter. The described spacing of the plate 76 provides an insulated area around the same by means of which the holder may be carried. A lug 77 on the plate 76 is extended into the thickened end of the plate 60 for the attachment of wiring thereto at a point protected by said thickened end for reasons which will be understood. A binding post 78 extends through the thickened end of said plate 60 to the lug 77 for the attachment of a wire, not shown, to said lug 77. By selected adjustment of the bars 64 and 68 different sizes of test and key sheets may be aligned at their edges and secured in relatively fixed position, one on the other, between said bars and the shoulder 63. As will be understood the described modified form of holder is designed for use with test and key sheets such as those previously described and also for use in conjunction with the combined registering and marking instrument 2 described in the foregoing.

In the modified adaptation of the invention illustrated in Figures 8 and 9, a color sheet 79 is utilized beneath the key sheet 80, the test sheet 81 being superposed on the key sheet just as described with reference to the preferred embodiment of the invention, it being understood that said sheets 79, 80 and 81 may be inserted in either of the previously described form of holders 1 or 55 81. With the color sheet 79 disposed under the key sheet 80 registering perforations in said key sheet and test sheet will expose to view a color spot as at 82. By counting the color spots in each column of answer selecting numbers 83 the 60 number of correct answers made by the student may be ascertained as will be clear.

The foregoing description will, it is believed, suffice to impart a clear understanding of my invention without further explanation.

Manifestly the invention, as described, is susceptible of modification other than as described, and right is herein reserved to all such modifications falling within the scope of the claims appended hereto.

What I claim is:

1. In apparatus of the class described, a frame like holder comprising a base forming an electrical conductor, a plurality of sheets having rows of perforations therein and adapted to be super-

- posed on said base with the rows of perforations in said sheets in registration and exposing areas of said plate therethrough, and a combined registering and marking instrument separate from said base and adapted to be wiped manually over the top sheet along selected rows of perforations thereof and electrically operative by contact with said exposed areas to register the number thereof and to mark said top sheet intermediate registering perforations, said instrument delineating a line as a mark.
2. An electrically operative instrument for use in counting registering perforations in sheets of paper superposed on a base and exposing the latter through said perforations, said instrument comprising a handle, a comb-like unit of resilient contact fingers mounted on one end of the handle to be wiped across the top sheet and engaged with the base through said perforations under manipulation of said handle, a counter on said handle, operating means for said counter including a solenoid adapted to be intermittently energized by such engagement of said fingers, and a marker mounted on said handle for movement in opposite directions relative thereto into marking and idle positions, respectively, said marker being normally in one position and operative by said operating means into the other position coincidentally with operation of the counter.
3. An electrically operative instrument for use in counting registering perforations on sheets of paper superposed on a base and exposing the latter through said perforations, said instrument comprising a handle, a comb-like unit of resilient contact fingers mounted on one end of the handle to be wiped across the top sheet and engaged with the base through said perforations under manipulation of said handle, a counter on said handle, operating means for said counter including a solenoid adapted to be intermittently energized by such engagement of said fingers, and a marker mounted on said handle for movement in opposite directions relative thereto into marking and idle positions, respectively, said marker being normally in one position and operative by said operating means into the other position coincidentally with operation of the counter.
4. In a holder for superposed perforated sheets and use with a counter electrically operative under control of feeler fingers thereon contacting said holder through said perforations, said sheets having a notch at one side edge and a pair of apertures at opposite sides thereof, a plate-like base of material forming an electrical conductor and of right angle form having upstanding edge keeper flanges of insulation material extending around the ends and one side thereof, a locator finger extending inwardly of the side flange for engagement by the notches of said sheets to center the latter on the base, and a pair of pins arising from said base for insertion through said pair of apertures to hold said sheets in centered position.
5. In a holder for superposed perforated sheets and use with a counter electrically operative under control of feeler fingers thereon contacting said holder through said perforations, a rectangular base including a top plate of material forming an electrical conductor for supporting the sheets, and means for squaring the sheets on said plate to register the perforations thereof comprising a sheet squaring bar secured at its ends to said base to extend longitudinally thereof and for adjustment transversely of the same into selected set positions, and a second similar bar secured to said first mentioned bar and to the base for adjustment longitudinally of said base and first mentioned bar into selected set positions.

KENNETH E. CONN. 40
